CONTROL DEVICE AND SYSTEM

Clarence Wantz, Milwaukee, Wis., assignor to
 Milwaukee Gas Specialty Company, Milwaukee, Wis., a corporation of Wisconsin

Application March 22, 1940, Serial No. 325,321

5 Claims. (Cl. 137—139)

This invention relates to improvements in control devices and, more particularly, is directed to an improved electromagnetic valve and to a thermoelectric safety shut-off system embodying such valve and operable to maintain a supply of fuel to a burner as long as a pilot light in juxtaposition to the burner is burning and automatically to shut off the fuel supply to the burner when the pilot light is extinguished.

In the illustrated embodiment of the invention, the electromagnetic valve comprises an electromagnet, an armature, and a valve which is closed when the armature is attracted to the electromagnet and is compelled to open position by retraction of the armature.

In the particular safety shut-off system selected for illustration and embodying the improved form of electromagnetic valve, I provide a diaphragm or other equivalent valve in the fuel supply pipe leading to the main burner, and by means of the improved electromagnetic valve I control the application of pressure to the diaphragm in such manner that the diaphragm valve remains open for the supply of fuel to the burner as long as the pilot light is burning and is automatically closed to shut off the supply of fuel to the burner when the pilot light is extinguished.

The adaptability of the electromagnetic valve to remain closed when the armature is attracted and to be compelled to open position by retraction of the armature, and the adaptability of the system to hold the valve in the fuel supply line leading to the burner open as long as the electromagnetic valve is closed and automatically to close the valve in the fuel supply line when the electromagnetic valve is opened provides a particular and advantageous correlation between the electromagnetic valve and the system.

The present invention also provides reset means for resetting the armature to attracted position, which reset means and the electromagnetic valve are so correlated that this valve is adapted to remain closed to shut off the flow of fuel through the valve part of the electromagnetic valve not only as long as the pilot light is burning, but also during the resetting operation.

Further features and advantages of the invention will be apparent from the following detailed description taken in connection with the accompanying drawings, in which:

Figure 1 is an elevational view of an electromagnetic valve embodying the present invention;

Figure 2 is an axial section through the elec-

tromagnetic valve and taken on the line 2—2 of Figure 1; and

Figure 3 is a more or less schematic view showing a thermoelectric safety shut-off system embodying the present invention.

The control device selected for illustration and designated in its entirety at 10, comprises a valve body 11 having an inlet 12 and an outlet 13.

A magnet mounting cup 14 formed of "Bakelite" or any other suitable or preferred insulating material is mounted upon the outer end of the valve body 11 and closes the outer end of the bore 15. The cup 14 has, at its inner end, an integral extension which fits into the counterbore 16, and the cup 14 is fastened in place by screws 17, preferably with a washer 18 between the cup and the valve body.

The magnet housing is in the form of an outwardly opening metal cup 20 mounted upon the mounting cup 14, for example by pressed fit engagement of its open outer end in the mounting cup 14, at 21. The magnet cup 20 is reduced at its inner end at 22, and the armature housing, which is also in the form of an outwardly opening metal cup 23, is mounted on the cup 20, for example, by pressed fit engagement of its outer open end telescopically over the reduced inner end of the cup 20. The inner end of the cup 23 is preferably reduced, as shown.

The electromagnet comprises a generally U-shaped magnet frame 25 positioned within the cup 20, with its legs extending through openings in the inner end of the cup 20 and presenting pole ends within the armature cup 23. The form of the magnet frame may be varied, and variations in the other parts of the device are also contemplated within the scope of the present invention. The particular magnet frame 25 selected for illustration has a threaded stud 26 integral therewith, or welded or otherwise joined thereto. This stud 26 extends into an opening or recess 27 in the mounting cup 14, and has threaded engagement with a nut 28 for clamping the magnet frame 25 rigidly and, at the same time, removably in place. The nut 28 has a kerf for engagement by a screw driver or other suitable tool, and a sealing washer 29 may be provided between the nut 28 and the inner end of the recess 27.

Fixed in the mounting cup 14 as, for example, by molding the insulating material of the cup thereto and extending endwise from the cup 14 are a pair of spaced metallic terminal connectors 30 and 31 having aligned openings and split outwardly of these openings as shown at 32. The

magnet coil 34 surrounds the legs of the magnet frame 25, and the leads or ends of this coil extend out into oblique openings 35 and have their bared ends connected to the terminals 39 and 31 in a manner to have good conducting contact therewith. The coil 34 is preferably covered with insulation between the bared ends at 38. If desired, suitable insulation may be provided between the turns of the coil and the legs of the magnet frame and between the inner end of the cup 20 and the adjacent end of the coil.

The armature 40 is disposed in the armature cup 23 and is adapted to be held in attracted position against the pole ends of the magnet frame 25 when the electromagnet is energized, as will presently appear. The armature 40 is of disk-like form and is secured to the outer end of the armature stem 42. The attachment of the armature to the armature stem 42 may be sufficiently loose or otherwise of a character to permit self-accommodation of the armature to the pole ends of the magnet frame 25 by a generally universal movement of the armature on the outer end of the armature stem. The stem 42 is disposed generally concentrically within the armature cup 23 and extends inwardly for reciprocatory movement through an opening 44 in the inner end of the cup 23.

An armature stem head 46 is secured by a pin 47 on the inner end of the stem 42. Packing 48 of felt or other suitable material is provided between the inner end of the armature cup 23 and a metal armature spring seating disk 49. The armature spring 50 is in the form of a coiled spring interposed between the head 46 and the spring seating disk 49. When the armature 40 is in attracted position, the spring 50 is compressed, and when the armature is released upon deenergization of the electromagnet, the spring 50 actuates the armature to retracted position and the valve to open position, as will presently appear.

The disk 49 seats inwardly upon a shoulder 52 in the bore of the valve body, and the action of the spring 50 tends to compress the packing 48 and maintain the same in sealing engagement with the bore of the valve body and with the armature stem 42 to seal the interior of the armature cup from the gaseous or other fuel which passes through the valve body and to seal the valve body against the escape of fuel out around the magnet mounting cup 14. The device is further sealed against the escape of fuel by the washer 18.

Threaded at 56 into the valve body 11 coaxial with the armature and armature stem is an annular valve seat member 58 having a valve opening 59 therethrough. The inner end of the valve seat member 58 has an annular valve seat 60 surrounding the inner end of the valve opening 59. Supported concentrically with the valve seat member 58, for example by the valve spring 62, is the valve member 64 shown as of disk-like form. The valve member 64 is provided with a leather washer or other yielding valve seating member 65 for engagement with the valve seat 60.

The spring 62, which is of coiled form, is interposed between the valve member 64 and a spring disk 65. As long as the armature 40 is in attracted position, this spring 62 maintains the valve member 64 closed against the seat 60, thereby shutting off the flow of fuel through the valve part of the electromagnetic control device. The spring disk 65 is slidable in the cooperating cylinder part of the valve housing in the resetting

operation, and a sealing member 68 fixed on the reset stem 70 for endwise movement therewith is interposed between the spring disk 65 and the adjacent end of the valve body. The sealing member 68 has a tapered or generally conical portion which, by means of the spring 62, is held seated against a cooperating annular seat or shoulder on the valve body to seal the opening through which the reset stem 70 extends when the reset stem is positioned as shown.

Coaxial with the valve member 64 is a valve stem 72 which has reciprocatory movement through the valve member. Threaded or otherwise secured on the outer end of the stem 72 is a valve stem head 74. When the armature 40 is released upon deenergization of the electromagnet, the spring 50 actuates the armature stem 42 and the armature 40 carried thereby inwardly to retracted position. In its movement to retracted position the armature stem head 46 engages the valve stem head 74, and the spring 50 being stronger than the spring 62, the valve member 64 is moved inwardly away from its seat 60 to open position, thereby allowing the fuel which enters the valve body 11 through the inlet 12 to pass through the valve opening 59 and out through the outlet 13. The valve member 64 is held open as long as the armature is in retracted position.

For the purpose of resetting the armature 40 to attracted position, the reset stem 70 is mounted coaxial with the valve stem 72 and for reciprocatory movement in the inner end of the valve body 11. The outer end of the reset stem 70 has a reset knob or button 79, and the inner end of this stem is tapered for cooperation with the tapered recess 80 in the adjacent end of the valve stem 72. The end of the valve stem 72 has a radially extending shoulder 81, and a coiled spring 82 is interposed between this shoulder 81 and the valve member 64 and normally maintains the valve stem 72 and the valve stem head 74 positioned as shown in Figure 2.

The invention can be embodied in a wide variety of forms for use with a wide variety of devices but, for purposes of illustration, the invention has been shown more or less schematically as embodied in a manner automatically to close a valve in a fuel supply pipe leading to a burner when the pilot light for the burner goes out.

In Figure 3 of the drawings, the burner 90 is any suitable or preferred main burner, such as the burner of a room or space heater, water heater, floor furnace, or any other burner. A fuel supply pipe 91 leads to the burner 90 for the delivery of gaseous or other fuel thereto, and a suitable valve, such, for example, as a diaphragm valve 92, is positioned in the pipe 91.

The diaphragm valve 92 has a partition 93 dividing the interior thereof into an inlet chamber 94 and an outlet chamber 95. Formed in the partition 93 is a valve opening 96 having a valve seat 97 formed about the upper end thereof. A valve casing part 98 is suitably secured to the main valve casing part, and clamped marginally therebetween is the flexible diaphragm 99. The diaphragm 99 divides the space between the valve casing part 98 and a second partition 100 on the main valve body into an inner diaphragm chamber 102 and an outer diaphragm chamber 103.

The inlet chamber 94 of the valve communicates through openings 104 in the partition 100 with the interior of the inner diaphragm chamber 102 so as to subject the inner side of the

diaphragm to the pressure of the fuel in the fuel supply pipe 91. The diaphragm 99 carries at the center thereof a valve stem 106 which has reciprocatory movement in the partition 100. A valve member 108, shown as of disk-like form, is carried by the inner end of the stem 106 and is adapted to seat upon the valve seat 97 to shut off the flow of fuel to the burner 90. The valve member 108 is shown in open position, allowing fuel to flow through the pipe 91 to the burner 90, and the diaphragm is preferably provided with a suitable weight at 140 for actuating the valve 108 to closed position when pressure is applied to the outer diaphragm chamber 103 by the opening of the valve 64.

In juxtaposition to, or associated with, the main burner 90 is the usual or any suitable or preferred pilot burner indicated more or less diagrammatically at 110, which pilot burner is intended to remain lighted for the purpose of relighting the main burner. This pilot burner 110 is supplied with gaseous or other fuel by pipes 111 and 112, the pipe 111 being connected at 113 to the main fuel supply pipe 91 anterior to the valve 92. The pipe 111 is also connected at 115 to a pipe 116 which leads to the inlet 12 of the electromagnetic control valve 10, and is suitably connected thereto. A pipe 118 leads from the outlet 13 of the electromagnetic control valve 10 to the outer diaphragm chamber 103 for supplying fuel under pressure into this chamber when the electromagnetic control valve is open.

While any other suitable or preferred form of thermocouple and lead connection may be employed within the scope of the broader aspects of the present invention, the particular thermocouple and lead connection shown in the drawings are of the general character disclosed and claimed in Oscar J. Leins Patent No. 2,126,564, granted August 9, 1938. The thermocouple designated in its entirety at 120 comprises an outer tubular metallic thermocouple member 121 and an inner metallic thermocouple member 122 disposed within the outer thermocouple member and joined at one end to the end of the outer thermocouple member to form the thermal junction 123 which is placed in position to be heated by the pilot light as shown in Figure 3. An inner lead conductor 124 is joined to the inner thermocouple member to form an internal thermal junction 125, and an outer tubular lead conductor 126 is connected to the outer tubular thermocouple member, for example through a sleeve 127, to form a third thermal junction 128. The outer lead conductor and outer thermocouple member enclose the inner lead conductor and inner thermocouple member. The inner lead conductor 124 is insulated from the outer lead conductor 126, for example, by a wrapping of insulation on the inner lead conductor.

The inner and outer lead conductors are preferably of a character that will permit bending as desired to permit disposing the thermocouple in any desired position. At the same time, the lead connection is preferably of a character to support the thermocouple in any desired position, although the thermocouple may have any other desired support such as, for example, on the pilot burner. At the opposite end, the inner lead conductor 124 extends from the outer lead conductor 126 and has a metallic terminal sleeve 130 fixed thereon in good conductive contact therewith and spaced from the end of the outer lead conductor 126. An insulating sleeve 132 is interposed between the ter-

5 minal sleeve 130 and the adjacent end of the outer lead conductor 126.

The thermocouple is connected to the terminals 30 and 31 of the electromagnetic control valve by slipping the terminal end of the thermocouple lead means through the opening 134 in one terminal 30 and into the opening 134 in the other terminal, with the terminal sleeve 130 in the opening 134 in one terminal 31 and the end 10 of the tubular thermocouple lead 126 in the opening 134 in the other terminal 30. The screws 135 are then tightened to clamp the split portions 32 of the terminals 30 and 31 into good conductive contact and gripping engagement with the terminal sleeve 130 and tubular lead 126, respectively. The thermocouple is disconnected from the electromagnetic control valve by loosening the screws 135 and withdrawing the terminal end of the thermocouple leads 15 from the terminals 30 and 31.

The operation is as follows:

When the pilot light 10 is burning, the heat thereof on the thermal junction 123 produces a thermoelectric current in the coil 34. The magnet frame 25 and armature 40 are preferably formed of an alloy of relatively low magnetic reluctance, and, as a result, the relatively weak thermoelectric current produces a magnetic field of sufficient strength so that when the armature 40 is placed in contact with the pole ends of the magnet frame by pushing the reset stem 70 inwardly, the magnetic attraction holds the armature in attracted position against the magnet frame with a force greater than the force exerted by the spring 50. The armature stem head 46 being at this time clear of the inner end of the valve stem head 74 as shown in Figure 2, the valve spring 62 moves the valve 64 to closed position and maintains this valve in this position to shut off the flow of fuel through the valve part 20 from the terminals 30 and 31.

If the pilot flame is extinguished, the holding action of the electromagnet ceases to be sufficient to hold the armature 40 in attracted position, and the spring 50 moves the armature to retracted position. The armature stem 42 moves inwardly to retracted position with the movement of the armature, and its inner end or the armature stem head 46 thereon engages the end 30 of the valve stem head 74 and actuates the valve 64 to open position. As already pointed out, the spring 50 is sufficiently stronger than the spring 62 to accomplish this result. Thus, movement of the armature 40 to retracted position moves the valve to open position, and this valve 64 is maintained open as long as the armature is retracted.

When it is desired to reset the device, the reset stem 70 is pressed inwardly, and by engagement 60 of its inner end with the end of the valve stem 72 the valve stem is moved inwardly through the valve member 64, moving the valve stem head 74 into contact with the armature stem head 46 so that continued inward movement of the reset 65 stem will move the armature to attracted position. The valve 64 is adapted to remain closed during the resetting operation; also, as long as the pilot light is burning.

If the pilot burner is lighted and sets up a 70 thermoelectric current to hold the armature in attracted position, the valve 64 will remain closed when the reset stem is released. If, on the other hand, the pilot burner is not lighted to produce the thermoelectric current for holding the armature in attracted position, the armature will be

actuated to retracted position to open the valve 64 upon release of the reset stem.

When the valve 64 is opened upon extinguishment of the pilot burner, a supply of fuel is delivered through the pipes 111 and 118 into the valve chamber of the electromagnetic control device, through the valve opening 58 and pipe 118, into the outer diaphragm chamber 103. A bleed tube 124 is provided for bleeding the fuel from the outer diaphragm chamber 103, this bleed tube 124 being of smaller diameter, or otherwise restricted, to permit pressure to be built up within the outer diaphragm chamber 103 when the valve 64 is open.

The building up of pressure in the outer diaphragm chamber 103 by the opening of the valve 64 upon extinguishment of the pilot burner results in overcoming the pressure on the inner side of the diaphragm sufficiently to actuate the valve 108 to closed position to shut off the supply of fuel to the main burner. This building up of pressure in the outer diaphragm chamber 103 may be only sufficient to equalize the pressure on opposite sides of the diaphragm, and the valve 108 may be weighted to close, or provided with other means for closing, the same when that is accomplished. The bleed tube 124 provides pressure release means for relieving the pressure in the outer diaphragm chamber 103 when the valve 64 is closed. The bleed tube preferably 30 delivers the gas which is vented from the outer diaphragm chamber 103 into the furnace or adjacent the main burner or the pilot burner, so that it may be consumed in the operation of the system. The amount of gas or fuel which is vented from the outer diaphragm chamber 103 through the tube 124 is relatively restricted, so that there will be no danger in the free escape thereof even with the main burner and the pilot burner extinguished. Whenever the valve 64 is 40 closed to shut off the application of pressure to the outer surface of the diaphragm 99, the discharge of fuel through the bleed tube 124 is discontinued except to the extent necessary to vent the fuel in the chamber 103 and the connected pipes.

The showing of the fuel supply pipe 91 leading to the burner 90 is more or less diagrammatic, it being understood that this fuel supply pipe may be provided with a mixing chamber (not shown) usually in proximity to the burner to which air is admitted in the usual way, as well understood in the art.

I do not intend to be limited to the precise details shown or described.

I claim:

1. In combination, a valve body, an electromagnet mounted on said valve body, an armature for said electromagnet, a valve seat in said valve body, a valve member, means urging said valve member into closed position against said valve seat as long as said armature is in attracted position, a valve stem having reciprocatory movement through said valve member and provided with a valve stem head presented toward said armature, and an armature stem carried by said head for actuating said valve to open position by retraction of said armature.

2. In combination, a valve body, an electromagnet mounted on said valve body, an armature for said electromagnet, a valve seat in said valve body, a valve member, means urging said valve

member into closed position against said valve seat as long as said armature is in attracted position, a valve stem having reciprocatory movement through said valve member and provided with a valve stem head presented toward said armature, an armature stem carried by said armature and cooperable with said valve stem head for actuating said valve to open position by retraction of said armature, and a reset stem disconnected from said valve stem and cooperable therewith for resetting said armature to attracted position.

3. In combination, a valve body, an electromagnet mounted on said valve body, an armature for said electromagnet, means for sealing said electromagnet and said armature from the interior of the valve body, a valve seat in said valve body, a valve member, means urging said valve member into closed position against said valve seat as long as said armature is in attracted position, means for actuating said armature to retracted position, a valve stem having reciprocatory movement through said valve member and provided with a valve stem head presented toward said armature, and an armature stem carried by said armature and cooperable with said valve stem head for actuating said valve to open position by movement of said armature to retracted position.

4. In a device of the class described, in combination, means comprising an armature and an electromagnet effective when energized for holding said armature in attracted position but ineffective to move said armature to attracted position, a valve member actuated to open position by movement of said armature to retracted position, means for holding said valve member in closed position as long as said armature is in attracted position, said armature having generally rectilinear movement to attracted and retracted positions and said valve member having generally rectilinear movement to open and closed positions, and reset means comprising a member having rectilinear sliding movement through 45 said valve member for resetting said armature to attracted position, said reset means being normally disposed in an outwardly projected position and movable to said position free of said valve member upon completion of the resetting operation.

5. In a device of the class described, in combination, means comprising an armature and an electromagnet effective when energized for holding said armature in attracted position but ineffective to move said armature to attracted position, a valve body, a valve member disposed within said valve body and actuated to open position by movement of said armature to retracted position, means for holding said valve member in closed position as long as said armature is in attracted position, said armature having generally rectilinear movement to attracted and retracted positions and said valve member having generally rectilinear movement to open and closed positions, and reset means comprising a first member having rectilinear sliding movement through said valve member and a second member disconnected from said first member and cooperating therewith for resetting said armature to attracted position, said second member being normally disposed in an outwardly projected position and movable to said position free of said valve member upon completion of the resetting operation.

CLARENCE WANTZ.
